UNITED STATES PATENT OFFICE

JEFFREY JOHN WALLACE, OF AMITE, LOUISIANA, ASSIGNOR TO GULLETT GIN COMPANY, OF AMITE, LOUISIANA

END DOOR LIFT MECHANISM

Application filed June 15, 1928. Serial No. 285,744.

This invention relates to lifting mechanism for the end doors of cotton presses.

In practically all cotton baling presses, the end doors are not fastened in any way to the press; they are set in place between the hinged front and rear doors, and are held in place by channels fixed to the front and rear doors and overlapping the side edges of the end doors. When the side doors are opened after a baling operation, the press operator must lift these end doors out bodily from the press and place them aside until the press is to be prepared for another operation.

In the latest type modern presses, these doors are very heavy. The matter of removing and replacing them is, therefore, a time consuming and expensive task; and some mechanical means is therefore desirable to effect their manipulation.

The main object of the present invention, therefore, is to provide baling presses with a simple and inexpensive means for handling these heavy end doors both in placing them in proper place in the press and removing them when desired.

Other objects of the invention will become apparent as the description proceeds.

In the drawings:

Figure 1 is a front elevation of a double up-packing baling press, showing one box thereof below the trumper, and the other box with the front and rear doors lowered and end doors held to permit removal of a wrapped bale;

Figure 2 is a fragmentary perspective of the present invention as applied to an end door of a cotton press;

Figure 3 is a horizontal section through a press box taken above the end door operating mechanism;

Figure 4 is a fragmentary vertical sectional elevation through one corner of the press box, showing front and end doors closed; and

Figure 5 is a vertical section showing an end door in open position.

Referring to the drawings:

The invention is shown, particularly in Figure 1, as applied to the press boxes of a double revolving up-packing baling press.

The press boxes 1 and 2 revolve about a central standard 23 to bring each box alternately under a trumper 4 and above a hydraulic ram 5.

The press box 2 is shown in Figure 1 in closed position and with the part disposed so as to receive cotton from the trumper 4 preparatory to being baled and wrapped. The press box 1 is shown with the front and rear doors thereof swung about their hinges to a horizontal position, and with the end doors swung upwardly and outwardly from contact with the bale of cotton to facilitate wrapping of the bale and to permit removal of the wrapped bale from the press.

The front door is designated by the reference numeral 6 and each of the end doors is designated by the reference numeral 7. Since each of the end doors is operated by identical lifting mechanism a detailed description of one door with the mechanism connected thereto will be sufficient to disclose the invention; and the corresponding parts of this mechanism will be identified by the same reference numerals wherever shown in the several figures of the drawings.

Referring particularly to Figure 2, there is shown one of the end doors 7 having a beveled lower edge 25 and secured adjacent thereto a pair of hook members 8 and 9 provided with bent over lugs 10 and 11, respectively, to receive a crank arm 12 formed between aligned bearing parts 13 and 14 of a rod 15 adapted to be rotated about said bearing parts 13 and 14 to lift the door 7 upwardly and its beveled edge 25 engaging lugs 20 and outwardly from the press box.

The part 14 has a handle extension 16 extending therefrom; and the parts 13 and 14 are journaled in bearings 17 and 18 formed in brackets 19 and 20, respectively, which are secured suitably to the web 21 of a channel iron 22 extending across the end of the press box.

It is to be noted that the lugs 10 and 11 and the bearings 17 and 18 do not embrace the crank arm 12 nor the bearing parts 13 and 14, so that the door 7, crank rod 16 as a whole, and the brackets 19 and 20 may be readily

disassembled by merely lifting the door away from the rod 16.

As shown particularly in Figures 4 and 5, the members 16, lugs 10, and brackets 19 and 20, are so proportioned that when the door 7 is raised from closed position, shown in Figure 4, to the open position, shown in Figure 5, the door 7 has its lower end supported by the brackets 19 and 20 in such position that the door is held open by gravity.

The end doors 7 on opposite sides of the pivot standard 23 are moved into and out of operative position by crank arm mechanism identical with the mechanism on the other 15 end doors, except that brackets 19 and 20 are replaced by small standards 20', identical in their slotted bearing ends with brackets 19 and 20 and suitably secured to a supporting plate 24 connecting the press boxes 1 and 2.

20 These intermediate end doors are operated in exactly the same manner as the outer end doors.

It will be apparent from the disclosure that I have provided an exceedingly simple and 25 inexpensive mechanism for raising and lowering the heavy end doors of cotton baling presses and which enables the doors to be readily removed from the press by merely lifting them off the crank arms 12. It will 30 also be apparent from the drawings that when the lever arms 16 are operated to lift the doors to open position, the doors will stay open by their own weight resting on the brackets 19 and 20 until the levers 16 are 35 operated in the opposite direction to move the end doors into closed position.

What I claim is:

1. In a cotton baling press, supporting 40 framework, a pair of side doors hinged to said framework, a pair of end doors movable bodily into and out of position between said side doors to form therewith a baling box, brackets fixed to said framework below the lower ends of said end doors having upward- 45 ly open notches, lugs fixed to the lower ends of said doors having downwardly open hooks, and crank shafts bearing in said bracket notches and lug hooks to lift said end doors and move them outwardly from baling position.

50 2. The combination set forth in claim 1, in which the parts are relatively proportioned so that the lower ends of the end doors when in open position rest on said brackets 55 and have their upper ends supported by said framework.

3. In a cotton baling press, supporting 60 framework, a press box having a bodily movable end door, lugs secured to the lower end 65 of said door and each shaped to form an open hook, brackets fixed to the framework and having open notches formed in the ends thereof and a crank shaft seated in said hooks and slots to move said door bodily into and out of 70 a predetermined location in said box.

4. In a cotton baling press having a bodily removable door, a downwardly open hook member mounted on the door adjacent its bottom edge, a crank member, and a lug mounted on the press under and adjacent the hook, said lug having an upwardly open notch positioned outwardly from the hook the length of the crank throw whereby said crank will pivotally engage said hook and notch as and for the purposes specified.

5. In a cotton baling press, a door having a beveled lower edge, a pivot member located on the press adjacent the bottom of the door and spaced outwardly from that face of the press and means bearing on that pivot for lifting and rocking the door upwardly and outwardly until its bottom edge engages the pivot member to secure same in opened position.

In testimony whereof I affix my signature.

JEFFREY JOHN WALLACE.
